UNITED STATES PATENT OFFICE.

OTTO JOHNSON, OF BROOKLYN, NEW YORK.

EXTENSIBLE PISTON-RING.

SPECIFICATION forming part of Letters Patent No. 703,590, dated July 1, 1902.

Application filed May 25, 1901. Serial No. 61,827. (No model.)

To all whom it may concern:

Be it known that I, OTTO JOHNSON, of the borough of Brooklyn, New York, N. Y., have invented a certain new and useful Improvement 5 in Extensible Piston-Rings, of which the following is a specification.

This invention consists of a circumferentially-extensible piston-ring, means for applying elastic pressure thereto in a direction 10 tending to circumferentially extend it, and a locking device for taking up such elastic pressure when the piston-ring has acquired a close sliding fit with the cylinder, whereby the piston-ring may thereafter reciprocate 15 without exerting the radially-outward pressure upon the wall of the cylinder, which is the cause of the wear of cylinders and piston-rings as ordinarily constructed.

The accompanying drawings, illustrating 20 the invention, are as follows:

Figure 1 is a piston-ring composed of two segments constructed with rabbeted slip-joints and with two sets of expanding-springs and two locking devices presenting abutments for taking up the thrusts of the springs 25 respectively. Fig. 2 is a view representing on a larger scale than Fig. 1 the details of construction of one of the rabbeted slip-joints, the system of expanding-springs, and 30 its locking device for limiting the range of circumferential extension of the packing-ring. Fig. 3 is an elevation showing a portion of the periphery of the ring at one of the joints. Fig. 4 is an isometrical perspective of a group of superposed liners. Fig. 5 is an elevation showing the arrangement of the system E of expanding-springs in the cell D.

The main piston-ring embodying the present 40 invention may be made in one piece if intended for use with cylinders of moderate diameter or may be made with any desired number of segments when made for use with cylinders of large diameters. Thus Fig. 1 represents a piston-ring made of two segments A and B, connected by two rabbeted slip-joints.

It will be understood that for a small cylinder one of the rabbeted slip-joints shown 45 in Fig. 1 will be omitted and the main part of the piston-ring be made of a single piece of metal. As the rabbeted slip-joints are

alike in construction, the subjoined description of one of them will suffice. It may be assumed that Fig. 2 represents the rabbeted 55 slip-joint as connecting the adjacent ends of two segments A and B. The rabbeted joint is composed of the relatively short underlapping member formed of the inward offset a of one end of the segment A and the relatively longer overlapping member b, constituting an extension of the adjacent segment B.

On its inner side the overlapping member b is provided with an inwardly-projecting boss 65 b', having a thickness in a radial direction corresponding to the thickness in a radial direction of the underlapping member a. A locking-bar c, bearing upon the concave faces of the member a and the boss b', is secured 70 to the main segment A and the main segment B by the screw-bolts c' and c'', which are inserted through slotted apertures in the offset portions c³ and c⁴ of the locking-bar c. The space within the locking-bar c and between 75 the extremity of the underlapping member a and the boss b' constitutes the cell D for containing the system E of expanding-springs, the action of which tends to extend the piston-ring circumferentially. The preferred 80 construction of these springs is that illustrated in Figs. 2 and 5. As shown, each spring e is made of a flat ribbon of steel bent approximately into the form of an ellipse. Any desired number of these springs can be 85 forced into the cell D.

The thrust of the system of springs against the extremity a' of the inwardly-offset underlapping member a is taken up by the undercut joint a² between the opposed extremity of the 90 offset underlapping member a and the outwardly-offset portion c³ of the locking-bar c.

The thrust of the springs in the opposite direction is delivered against the end b² of the boss b' and is taken up by the system F 95 of liners, which are shown as introduced between the undercut end b³ of the boss b' and of the correspondingly-inclined shoulder c⁵ of the outwardly-offset portion c⁴ of the locking-bar c.

It will of course be understood that some or all of the liners may be introduced into the undercut joint a² without altering the result or departing from the invention.

What is claimed as the invention is—

1. A rabbeted slip-joint for connecting the meeting ends of a circumferentially-extensible piston-ring, the said joint composed of a relatively long overlapping member provided with an inwardly-projecting boss; and an inward offset forming a relatively shorter underlapping member; an expanding-spring system interposed between said boss and the opposed end of the said inward offset forming said underlapping member; a locking-bar provided upon its radially outward face with a recess for receiving said boss and said inward offset; a system of liners appropriately introduced into said recess for limiting to a prescribed extent the circumferentially-expanding influence of said spring system upon the members of said joint.
2. In a circumferentially-extensible piston-ring, a rabbeted slip-joint; an expanding-spring system tending to separate the members of said rabbeted joint in such direction as to circumferentially extend said piston-ring; a locking-bar provided upon its radially-outward side with a recess having oppositely-undercut ends, presenting bearing-faces parallel with correspondingly undercut faces formed respectively upon the inwardly-offset underlapping member of said joint and upon a boss projecting inwardly from the overlapping member of said joint, and a prescribed number of liners introduced into one or both ends of said recess for the purpose of taking up the elastic pressure of said expanding-spring system and thereby relieving the piston-ring therefrom.
3. In a piston-packing, the combination of a divided and circumferentially-expansible

piston-ring, means for exerting elastic pressure on said ring to expand the same to fit a surrounding surface, a locking-bar joining the ends of the divided ring, and means adapted to be interposed between the locking-bar and an end of the expansible piston-ring to limit the action of the elastic expanding means and relieve the surface of further expanding pressure when the fit between the ring and surface has been secured.

4. In a piston-packing, the combination of a divided and circumferentially-expansible piston-ring, means for exerting elastic pressure on said ring to expand the same to fit a surrounding surface, a locking-bar joining the ends of the divided ring, and removable liners adapted to be interposed between the locking-bar and an end of the expansible piston-ring to limit the action of the elastic expanding means and relieve the surface of further expanding pressure when the fit between the ring and surface has been secured.

5. A piston-packing comprising a circumferentially-expansible piston-ring having a slip-joint, an expanding-spring system interposed between the abutments of said joint to circumferentially expand the ring to fit a surrounding surface, a locking-bar secured to both members of the slip-joint, and removable liners coacting with said locking-bar to limit the expanding action of the spring system and lock the ring against further expansion when the fit between the ring and the surrounding surface is secured.

OTTO JOHNSON.
